UNITED STATES PATENT OFFICE.

JOHN J. TOWER, OF MONTCLAIR, NEW JERSEY.

DESIGN FOR A HANDLE OF SCREW-DRIVERS OR SIMILAR ARTICLES.

No. 37,995.

Specification for Design.

Patented May 8, 1906.

Application filed March 28, 1906. Serial No. 308,620. Term of patent 14 years.

To all whom it may concern:

Be it known that I, JOHN J. TOWER, a citizen of the United States, residing at Montclair, in the county of Essex and State of New Jersey, have invented a new, original, and ornamental Design for Handles of Screw-Drivers or Similar Articles, as shown in the accompanying drawings.

Figure 1 is a plan view, and Fig. 2 is an end

view, of a handle of a screw-driver or similar article, showing my design.

I claim—

The ornamental design for the handle of a screw-driver or similar article as herein shown.

JOHN J. TOWER.
